UNITED STATES PATENT OFFICE

126,953

DESIGN FOR A JACKET OR SIMILAR ARTICLE

Isaac Kirschenbaum, Middletown, Pa.

Application January 30, 1941, Serial No. 98,534

Term of patent 7 years

To all whom it may concern:

Be it known that I, Isaac Kirschenbaum, a citizen of the United States, residing at Middletown, in the county of Dauphin and State of Pennsylvania, have invented a new, original, and ornamental Design for a Jacket or Similar Article, of which the following is a specification, reference being had to the accompanying drawing, forming part thereof.

I claim:

The ornamental design for a jacket or similar article, as shown.

ISAAC KIRSCHENBAUM.
